UNITED STATES PATENT OFFICE

HARRY LUBIN, OF SOUTH ORANGE, NEW JERSEY

BOX

Application filed July 17, 1931. Serial No. 551,487.

An object of the invention is to provide an inexpensive and durable crate or box which is constructed in a manner which will permit a number of the crates to be packed in a small space. The crate while securely bound is without projections which might prevent one of the crates from sliding into place between other crates. The binding means for the crate also serve to prevent a side or bottom member of the crate from being slid out of place to reach the interior of the crate.

Another object of the invention is to provide an inexpensive cover for the crate or box which while it is normally held in place the construction is such that it may be conveniently removed. The crate or box has at the upper portions of its ends bearing members extending inwardly, and the cover which is resilient has transverse bearing members extending beyond the sides of the cover intermediate of the ends thereof, and transverse members spaced from the ends of the cover. This construction permits the disposal of an end of the cover under a bearing member at an end of the crate or box, and with the bearing member intermediate of the ends of the cover resting on the sides of the crate or box. The other end of the cover may then be pressed downwardly and the cover slid to a position where both its ends will be disposed under the bearing members on the crate or box.

Additional objects of the invention will appear in the following specification in which the preferred form of the invention is described.

In the drawing similar reference characters refer to similar parts in all the views in which—

Figure 1 is a perspective view showing the crate or box.

Figure 2 is a transverse sectional view of Figure 1.

Figure 3 is an enlarged perspective view illustrating the cover of the box.

Figure 4 is an enlarged longitudinal sectional view of the crate or box showing the cover in normal position, and

Figure 5 is a fragmentary sectional view illustrating how the cover may be removed from the crate or box.

By referring to the drawing, it will be seen that the crate or box has a bottom 10, sides 11, and ends 12, the crate or box having bearing members 13, which are disposed transversely at the ends of the crate or box, the bearing members extending inwardly from the upper portions of the said ends of the crate or box.

It will also be seen by referring to Figure 4 of the drawing that the crate or box has members 14 which as shown in the drawing are disposed at the corners of the crate or box, and which are spaced below the bearing members 13. The ends 12 are bound to the sides 11, and the bottom 10 by binding wire 15, there being preferably two of these binding wires 15, which are disposed in the grooves 16 at the top of the ends 12, in grooves 17 in the sides 11 of the box, and in grooves 18 in the bottom 10 of the box. It will, therefore, be seen that these binding wires 15 will serve to hold the ends, the sides and the bottom portions of the box together, and that it will be impossible to slip a side or bottom member out of position to reach the interior of the crated boxes, and it will also be impossible to remove an end of the crate or box.

It will also be seen by referring to the drawing, and particularly Figure 2 of the drawing, that while the binding wires 15 serve to hold the parts of the crate or box in position, the binding wires 15 do not project beyond the bottom, the sides, or the top of the crate or box, and that, therefore, the binding wires 15 will not prevent the ready movement of the crate or box in position by slipping the crate or box between adjacent crates or boxes.

The cover for the crate or box is illustrated in Figure 3 of the drawing, and this cover which is resilient is preferably made of longitudinally extending resilient members 19 which are spaced apart and which are connected by transverse members 20 and 21. The transverse member 20 is disposed between the ends of the cover and it has projecting ends 22 which normally engage the upper portions of the sides 11 of the crate or box as illustrated in Figure 1 of the drawing. When the cover is in normal position it is disposed as is illustrated in Figure 4

- of the drawing, where the transverse members 21 are disposed substantially in alignment with the inner ends of the bearing members 13 on the crate or box, and the ends of the members 19 beyond the transverse members 21 are disposed below the said bearing members 13, the ends 22 of the transverse member 20 being disposed at the top of the sides 11 of the box as has been explained.
- When it is desired to remove the cover of the crate or box, an end of the cover is pressed downwardly, so that the transverse member 21 at the said end 23 may be moved under a bearing member 13, when the cover is slipped in the direction of the said bearing member. This frees the opposite end 24 of the cover from the other bearing member 13 and permits the raising of the said end 24 of the cover, so that the end 23 may be removed from under the bearing member 13. The upper ends of the members 14 limit the downward movement of the ends 23 and 24 of the cover when the cover is adjusted in position, and also when the cover is removed from the crate or box.
- When the cover is to be adjusted on the crate or box, the cover is disposed in the position illustrated in Figure 5 of the drawing, when the end 24 of the cover is pressed downwardly and under the adjacent bearing member 13 until the transverse member 21 at the said end 24 of the cover is disposed under the said bearing member 13. When this is done, the transverse member 21 of the other end 23 of the cover is moved from under the adjacent bearing member 13 and the cover assumes the position as illustrated in Figure 4 of the drawing.
- What is claimed:
1. A crate or box having sides and ends and transverse bearing members extending inwardly from the upper portions of the ends of the crate or box, a resilient cover having a transverse member disposed intermediate of its ends and extending beyond the sides of the cover and engaging the sides of the crate or box, and transverse members spaced from the ends of the cover and normally disposed at the bearing members on the crate or box, with the ends of the cover beyond the last mentioned transverse members disposed under the said bearing members, and corner members in the box which are spaced from the undersides of the transverse bearing members to form guideways below the transverse bearing members which are terminated at their outer ends by the ends of the box, the guideways serving to receive the last mentioned transverse members with the cover adjacent thereto when the cover adjacent a transverse member is pressed downwardly and is moved in the direction of the adjacent end of the crate or box.
  2. A cover for a crate or box having sides and ends and transverse bearing members

extending inwardly from the upper portions of the ends of the crate or box and constituting flanges, including a resilient longitudinal cover member, said longitudinal member being so constructed and arranged that its length is greater than the distance between the inner edges of the flanges of the crate or box and the portions at each end extending beyond the distance between the inner edges of the flanges of the crate or box are approximately one-half the width of said flanges, an end batten transversely of and rigidly secured to said longitudinal member adjacent each end thereof, said end battens being of a length substantially equal to the width of said longitudinal member and spaced from the ends thereof approximately one-half the width of the flanges whereby the outer edges of said battens will be spaced apart the distance between the inner edges of the flanges, and an intermediate transverse batten of greater length than the inside width of the crate or box between the sides thereof, said intermediate batten being rigidly secured to the longitudinal member and having portions extending beyond said longitudinal member at each side thereof, said extending portions being adapted to rest upon the side walls of the crate or box, the arrangement and construction being such that after one end of the longitudinal member with a portion of its end batten has been positioned under one of the flanges of the crate or box for the full width of the flange, the longitudinal member may be flexed sufficiently to cause the upper surface of the longitudinal member to be slightly below the lower surface of the opposite flange of the crate or box and then the cover caused to slip upon the extending portions of the intermediate batten to move the end batten from under the flange and the extending portion at the other end of the longitudinal member under the adjacent flange.
